UNITED STATES PATENT OFFICE.

ALANSON C. ESTABROOK, OF NORTHAMPTON, MASSACHUSETTS.

DESIGN FOR AN EYELET.

SPECIFICATION forming part of Design No. 25,796, dated July 21, 1896.

Application filed October 19, 1895. Serial No. 566,272. Term of patent 14 years.

To all whom it may concern:

Be it known that I, ALANSON C. ESTABROOK, a citizen of the United States, residing at Northampton, in the county of Hampshire and 5 State of Massachusetts, have invented and produced a new and original Design for Covered Eyelets, of which the following is a specification, reference being had therein to the accompanying drawings.

10 Figure 1 of the accompanying drawings shows in vertical transverse section an eyelet embodying my design and illustrating the essential features of the latter. Fig. 2 is a view of said eyelet in plan.

15 The essential features of my design comprise a tubular-shaped body terminating in a head on top of and surrounding said body, the said head having in cross-section the general shape of a semicircle, with the diameter of the said semicircle at right angles 20 with the upright lower portions of the sides of the said body. The inner portion of the said head is ornamented by an annular groove, below which is a slightly-swelled convex portion, the inner portion of the head thereby

presenting, when viewed from above, an ornamental beaded effect.

1 designates the tubular-shaped body of the eyelet, and 2 the head thereof. The lower portion of the said body is upright, while the 30 upper portion 3 thereof, adjacent the head, swells outwardly. As above stated, the head has in cross-section the general shape of a semicircle and its diameter arranged at right angles to the body of the eyelet. The smooth 35 inner surface of the head has an annular groove 4, extending around the same, below which is the swelled portion or hip 5, the said groove and swelled portion or hip producing an ornamental effect. 40

I claim—

The design for an eyelet substantially as shown and described.

In testimony whereof I affix my signature in presence of two witnesses.

ALANSON C. ESTABROOK.
